UNITED STATES PATENT OFFICE.

WILLIAM S. KING, OF SAN FRANCISCO, CALIFORNIA.

CENTERING FOR CONCRETE AND TILE CONSTRUCTION.

No. 893,328.

Specification of Letters Patent.

Patented July 14, 1908.

Application filed February 19, 1908. Serial No. 416,735.

To all whom it may concern:

Be it known that I, WILLIAM S. KING, citizen of United States, residing in the city and county of San Francisco and State of California, have invented new and useful Improvements in Centering for Concrete and Tile Construction, of which the following is a specification.

My invention relates to improvements in concrete, tile and like construction.

It consists in the construction and employment of temporary, adjustable and removable centering pieces, upon and about which the super-structure may be laid, said centering pieces being removable and adapted to be continually used in new work.

It also comprises details of construction which will be more fully explained by reference to the accompanying drawings, in which—

Figure 1 is a section showing the device applied. Fig. 2 is a plan view of a pair of plates. Fig. 3 is an end view of one of the plates showing the supporting piece 4.

In the laying of concrete floors which are supported by I-beams, and for similar construction, it is customary to make a centering of wood or the like upon which the concrete, a tiling, or equivalent filling is supported until it has properly set and hardened, after which the centering structure is removed, being usually destroyed in its removal.

It is the object of my invention to provide a metallic center which may be adjustably fixed in place, and is readily removed after it is no longer needed.

In the present drawings I have shown I-beams A, such as are commonly employed for floor and like structures.

2 are metal strips of any suitable or desired width and thickness having the ends adapted to lie flatwise against the beams, and being bent at their upper angles so that they stand edgewise across the space between the beams, as shown at 2^a. The flat portions 2 of these plates are perforated with holes, as at 3, and strips of metal 4 are formed, preferably with a plurality of holes, so that they may be bolted or otherwise secured through the holes 2. The free ends of these strips 4 are bent outwardly from the plates 2 so that they will rest upon the lower flanges of the beams A as plainly shown in Fig. 1. By means of the holes 3, these supporting pieces 4 may be raised or depressed to suit the

depth of the beams A, and the desired depth and character of the structure to be supported above the center and between the floor beams. As these beams may be set at various distances apart, I have shown them slotted as at 5, the slots registering with each other, and by means of bolts 6 they may be secured together by passing the bolts through the slots and tightening them up by nuts or otherwise.

It will be understood that separate holes may be substituted for the slots, but the latter are more convenient for close adjustment, and when thus properly adjusted, the divergent sides 2 will lie substantially close to the lower flanges of the beams A, and the plates 4 will support the structure at any desired distance below the level of the tops of the beams A. Wood or other material may also be used at 2.

The plates 2 extend below the bottom of the beams, converging toward each other as shown, and they are perforated with holes adapted to receive bolts 7 which extend through the holes a sufficient distance below the lower flanges of the beams A to admit of any desired protective filling at this point. The sets of center-pieces which lie in the spaces between each contiguous pair of floor beams are thus connected together, and the structure may be completed, extending over the full width of the superposed flooring, and as all of these are supported by the plates 4, it will be seen that a sufficiently strong and rigid centering is thus formed.

Upon the transverse portions 2^a of the center plates, boards may be laid as at 8, and upon the sides between the inclined portions 2^a and the beams, other boards 9 may be placed to form a support for the concrete, or other filling which occupies the space between and around the beams, and up to the level of their upper surfaces. Other boards 10 may be laid upon the bolts 7 and beneath the beams so that a concrete filling may be extended below the beams, and thus form an inclosing protecting and heat-resisting envelop for said beams.

When the filling and super-structure of concrete, tile, or other material (which is filled in in the plastic state) has become set and hardened, it is only necessary to remove the bolts 7, disengage the plates 2 from the supports 4, and loosen the bolts 6 so that the metal plates may all be moved away from the concrete and the beams, when they can be

removed. The boards 8, 9 and 10 are then easily removable, exposing the concrete or fireproof surfaces beneath, and properly arched or shaped; it being understood that 5 the plates 2 may be curved or otherwise shaped to form any desired lower surface for the concrete. In this manner I am enabled to employ the same structure for repeated uses, and it may be readily fitted to any permanent structure upon which it is to be employed.

Having thus described my invention, what I claim and desire to secure by Letters Patent is:

15 1. In a centering device for concrete and like construction, and in combination with beams having lower flanges, plates having their upper ends overlapping and arranged on edge, bolts by which said ends are adjust-
20 ably secured together, the lower portions of said plates being given substantially a quar-
ter-turn relative to the remaining portion of the plates and said lower portions extending downwardly contiguous to the lower flanges of
25 said beams, extensions on said plates adapted to rest upon the lower flanges of the beams,

and means whereby said extensions are adjustable on said plates.

2. In a centering device for concrete and like construction, the combination with floor 30 or I-beams, of adjustable overlapping plates extending edgewise between said floor or I-beams having bent portions projecting downwardly contiguous to and below the lower flanges of the beams, bolts by which 35 the lower ends of contiguous plates are connected together, supporting extensions fixed to the plates and having their free ends bent to stand edgewise from the plate and adapted to rest upon the lower flanges of the I- 40 beams, and boards supported by the top and sides of said plates and by the bolts and adapted to receive and support a plastic filling until said filling has become set and hardened.

45 In testimony whereof I have hereunto set my hand in presence of two subscribing witnesses.

WILLIAM S. KING.
